CLAIM

The ornamental design for a seat assist cushion, as shown and described.

DESCRIPTION

FIG. 1 is a top, front and right side perspective view of a seat assist cushion, showing my new design;

FIG. 2 is a bottom, rear and left side perspective view thereof;

FIG. 3 is a bottom, front and left side perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is a top, front and right side perspective view of the seat assist cushion in its closed state;

FIG. 11 is an enlarged view of portion 11 in FIG. 1; and, FIG. 12 is an enlarged view of portion 12 in FIG. 4.

The broken lines show the features of the seat assist cushion that form no part of the claimed design. The dash-dot-dash broken lines define the boundary of enlarged views and form no part of the claimed design.
